(57) **CLAIM**

The ornamental design for a blower bracket as shown and described.

DESCRIPTION

FIG. 1 is a front, left and top perspective view of a blower bracket, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the blower bracket that form no part of the claimed design.

The unshaded surfaces shown in broken or between solid and broken lines in FIGS. 2 and 7 forms no part of the claimed design.

1 Claim, 8 Drawing Sheets
